UNITED STATES PATENT OFFICE.

ROBERT H. MUELLER, OF DECATUR, ILLINOIS.

RELIEF-VALVE.

1,305,615.

Specification of Letters Patent. Patented June 3, 1919.

Application filed July 9, 1917 Serial No. 179,594.

To all whom it may concern:

Be it known that I, ROBERT H. MUELLER, a citizen of the United States, residing at Decatur, in the county of Macon and State 5 of Illinois, have invented new and useful Improvements in Relief-Valves, of which the following is a specification.

The present invention relates to pressure relief valves. It provides a valve construction which will give prompt and complete relief from excess pressure in fluid-carrying pipes, if, for any reason, such pressure should exceed the limit of safety for the system, the arrangement being such that if 10 the usual operating parts of the valve actuating mechanism should become deranged and fail to work in event of excess pressure, the valve would still be automatically operable to relieve pressure, this giving a 15 double element of safety from excess pressure.

In the drawings herewith I have shown one embodiment of my invention, and in said drawings:

25 Figure 1 is a view in vertical section of my relief valve, the valve casing proper being in elevation.

Fig. 2 is a view of the valve in side elevation at right angles to the view shown in 30 Fig. 1, the diaphragm casing being partly in section.

Fig. 3 is a top plan view, partly in section, of the diaphragm casing.

Fig. 4 is a transverse sectional view substantially on the line 4—4, Fig. 1, looking in the direction of the arrow, to show the valve-closing levers.

Fig. 5 is a view in vertical section of a relief valve in which the lever and spring arrangement are slightly different from the adaptation of the invention shown in Fig. 1.

Referring to the drawings by numerals, like numbers indicating like parts in the several views, 10 indicates a valve casing of 45 any suitable or desired type designed to be installed in the line and having a valve-seat 11 and a valve 12 adapted to seat thereon, and said valve and seat may be of any desired or usual type.

50 From the said valve 12 a stem 13 extends upwardly through a stuffing box 14 which is mounted in the base of a hollow supporting post or frame 15 which is preferably open through a part of its length, as at 16, to 55 give access to the interior of the hollow

post 15. The base or post 15 is secured by a fluid tight connection to the valve-casing 10, as best shown in Fig. 1, and has the radial extensions 17 which carry adjustable screws 18 supporting spring-engaging disks 19, which, together with the screws 18, serve as abutments for springs 20, two being shown in the present instance. The said springs 20 have similar disks 21 at their upper ends, which engage the outer ends of 65 levers 22 pivoted to lugs 23 preferably formed integral with the post 15. The inner ends of said levers 22 pass through suitable apertures in the post 15, and are pinned by pivot pins 24 to a cross-head 25 through 70 which the valve stem 13 passes and to which it is securely fastened, as by pin 26. Preferably the stem 13, which passes from the stuffing-box 14 upwardly through a guiding web 27 (see Fig. 1) projecting from the 75 post 15, will be of reduced diameter at the point where it is engaged by cross head 25, so that a shoulder 28 is provided upon which cross-head 25 rests.

It will be seen that by the arrangement 80 of springs and levers just described a downward, and, in the present instance, a closing thrust will be exerted by the levers 22 and springs 20 on the valve-stem and valve, and it will be clear that by varying the tension 85 of the springs by the screws 18, such thrust may be made greater or less, as may be desired.

The upper end of the valve-stem 13 projects into a diaphragm chamber 29 secured 90 in any suitable manner, as by screw-bolts 30 to the top of the post 15, and is screw-threaded or otherwise secured to a pivot-block 31. To said pivot-block are secured the inner and long ends of levers 32 pivotally 95 mounted in lugs 33 formed, in the present case, integral with the diaphragm casing 29. The outer and short ends of levers 32 are pivotally coupled to the depending arms of a diaphragm-operated yoke 34, these 100 pivot connections of levers, lugs, and yoke being sufficiently loose (as shown in dotted lines Fig. 1) to permit play of the parts as they operate and prevent binding.

The diaphragm chamber 29 is formed of 105 two parts, as is usual, and between them is clamped the diaphragm 35, dividing the chamber into two parts with the diaphragm 35 resting on the yoke 34 as best shown in Fig. 1. The part of chamber 29 above the 110

diaphragm 35, is, of course, fluid tight, and it has a pressure connection 36 through which pressure to control the valve 12 may pass, and which pressure tends to force the diaphragm and yoke downwardly and actuate the valve-controlling levers.

- It will be understood that at normal pressure the springs 20 and levers 22, acting on the valve stem 13 through cross-head 25 10 will keep the valve 12 closed. If, however, the pressure in the system becomes excessive, or if for any reason the system is to be relieved, the regulating pressure coming through connection 36 and standing against diaphragm 35, increasing beyond the point 15 at which the parts are set, will force diaphragm and yoke downward and throw the levers 32, lifting stem 13 and raising valve 12 from its seat, so as to relieve pressure in the system. It will be understood that this 20 movement of the diaphragm, levers, and stem takes place only when pressure is sufficient to overcome the tension of springs 20 and the closing thrust of the levers 22 which 25 tend to keep valve 12 in closed position. Immediately the pressure falls the closing springs 20 and levers 22 will return the valve to its closed position, and the parts in the diaphragm chamber to normal condition.
- It will be observed that the long ends 30 of the levers 32 project inwardly and engage the stem 13 while the outer and shorter ends are engaged by the yoke 34. By this arrangement a relatively slight movement of the diaphragm and yoke will impart an increased and quicker movement to the valve stem and valve, so that a rapid and full 35 opening of the valve is secured and quick relief given.
- It will be seen that the valve 12 is, through the stem 13, levers 22, and springs 20, held to its seat by spring-pressure only, so that the pressure in the system tends constantly to open the valve. It is always opened, 40 however, under proper condition of the parts, by the diaphragm yoke, and lever as described. If the opening mechanism in the diaphragm chamber should fail to operate, the valve would, nevertheless, relieve the system, for immediately the pressure on the underside of the valve 12 overcomes the tension of springs 20 it will open the valve and permit excess pressure to escape. This 45 gives, of course, a double element of safety, and a valve is provided which, under ordinary conditions will be perfectly and closely controlled for excess pressure, and which, furthermore, cannot be entirely blocked so far as relief is concerned even if the mechanism, which is normally effective to give 50 relief, is deranged.

In the form of the invention shown in Fig. 5, the valve casing 36 and its valve 37 will be generally of the same construction as 55 that shown in the other adaptations of the

invention, the stem 38 of the valve extending upwardly through a stuffing box 39 which stuffing box, as in the constructions hereinbefore described, is mounted in the base of a supporting post or frame 40 preferably of the same open construction as that shown in Fig. 1, the valve casing 36 and the supporting frame being secured together by a fluid-tight joint as shown. The supporting post 40 is provided with radial extensions 41 in which are mounted adjustable screws 42 engaging the disks 43, which form seats for springs 44, as in the constructions heretofore described. At the upper ends of the springs 44 are lever-engaging disks 45 which bear against the outer ends of levers 46 pivotally mounted on lugs 47 which, in the present instance, are shown as formed integral with the casing 40. The inner ends of the levers 46 engage a pivot block 47' 85 threaded or otherwise secured to the upper end of the valve stem 38 so that with this construction the springs 44, through the pivoted levers 47, tend always to force the valve stem 38 and close the valve 37. 90

The levers 47 outside of their pivot points are engaged by the depending ends of a yoke 48, which yoke bears against a diaphragm 49 mounted in a diaphragm chamber 50. The chamber 50 is preferably formed integral with the supporting post 40 and has the cut-away portions 51 to permit the levers 46 to project outwardly and be engaged by the springs 44. The diaphragm 49 is held in place by the cap 52, which 100 clamps the diaphragm in the usual manner to give a fluid-tight connection, said cap 52 having the pressure connection 53 coming from any suitable source and by means of which pressure may be exerted on the diaphragm and transmitted through the yoke 42 to the levers, valve stem and valve, so as to regulate and control the movements of the valves. 105

In operation, the valve 37 will normally 110 be held closed by the action of the springs 44 which engage the valve stem 38 and force the valve to its seat. When, however, the pressure in the system, or from the controlling source, becomes excessive, it will, 115 acting through the pressure connection 53, force the diaphragm 49 downwardly, carrying with it the yoke 48, which will compress the springs 44, tilt the levers 46, draw up the valve stem 38, and open the valve 37 to 120 release pressure.

With this construction, a very compact arrangement is provided, and one in which I am enabled to dispense with the independent set of levers for holding the valve 125 closed shown in the adaptation of the invention illustrated in Fig. 1, thus simplifying to some extent the construction.

Such changes as come within the range of mechanical skill and are equivalents of the 130

specific disclosures herein set forth; are to be regarded as within the scope of my invention.

I claim:

5. 1. In a device of the class described and in combination a valve casing, a valve therein, a diaphragm casing, a pressure controlled diaphragm therein to actuate said valve, a lever connection between said valve and diaphragm, spring actuated means engaging said lever connection to actuate said valve in opposition to said diaphragm, and means for adjusting the tension of the spring for said actuating means comprising 10 a disk at one end of the spring and an adjusting screw for moving said disk.
2. In a device of the class described and in combination, a valve casing, a valve therein; a diaphragm casing; a diaphragm 20 therein, a hollow post connecting said valve and diaphragm casings; a valve stem carrying a cross head, spring actuated levers oppositely arranged on said post and pivotally connected to said cross-head and means for 25 adjusting the tension of said springs movably mounted in the lower portion of said hollow post.
3. In a device of the class described, and in combination, a valve casing, a valve therein, a diaphragm casing, a diaphragm therein controlled by inlet pressure to open said valve, an open hollow post connecting said valve and diaphragm casing, a valve stem having a shoulder thereon traversing said 30 post and connecting said diaphragm and valve, levers pivoted to an integral part of said post on opposite sides thereof, a cross-head on the stem and engaging the shoulder thereon, the inner ends of said levers pivot- 35 ed to the cross-head and springs arranged on opposite sides of the post and engaging the outer ends of said levers tending to close said valve in opposition to said diaphragm.
4. In a device of the class described and in combination, a valve casing, a normally closed valve therein, a diaphragm casing having an inlet pressure connection, a diaphragm in said casing to open said valve, an open hollow post connecting said valve and diaphragm casings, a stuffing box between said valve casing and post, a valve 40 stem traversing said stuffing box and post and connected with said diaphragm, a cross-head on said valve stem, levers pivoted to an integral portion of the post and arranged on opposite sides thereof and engaging the cross-head at their inner ends, springs carried by said post engaging the outer ends of said levers to close said valve in opposi- 50 tion to said diaphragm and means carried by the lower end of said post for adjusting the tension of said springs.
5. In a device of the class described and in combination, a valve casing, a normally closed valve therein, a diaphragm casing 55 having an inlet pressure connection, a diaphragm in said casing to open said valve, an open hollow post connecting said valve and diaphragm casings, a stuffing box between said valve casing and post, a valve stem traversing said stuffing box and post and connected with said diaphragm, a cross-head on said valve stem, levers pivoted to an integral portion of the post and arranged on opposite sides thereof and engaging the cross-head at their inner ends, springs carried by said post engaging the outer ends of said levers to close said valve in opposi- 60 tion to said diaphragm and means carried by the lower end of said post for adjusting the tension of said springs.
6. In a device of the class described, and in combination, a valve casing, a normally closed valve therein, a diaphragm casing having a control pressure connection, a diaphragm in said casing to open said valve, an open hollow post connecting said valve and diaphragm casings and having a fluid-tight connection with said valve casing, a stuffing box between said valve casing and post, a shouldered valve stem traversing said stuffing box and post and connected with said diaphragm, a cross-head engaging said shouldered stem, levers pivoted on said post and engaging said cross-head at their inner ends, and adjustable springs mounted on said post and engaging the outer ends of said levers to close said valve in opposition to said diaphragm.
7. In a device of the class described and in combination, a valve casing, a normally closed valve therein, a diaphragm casing having a control pressure connection, a diaphragm in said casing, valve-operating levers in said casing connected with said diaphragm, an open post connecting said valve and diaphragm casing and having a sealed connection with said valve casing, a stuffing box between said valve casing and post, a shouldered valve stem traversing said stuffing box and post and engaging said operating levers in the diaphragm casing, a cross-head engaging said shouldered stem, levers pivoted on said post and engaging at their inner ends said cross head, and adjustable springs carried by said post and engaging the outer ends of said levers to close said valve in opposition to said diaphragm.
8. In a device of the class described, and in combination, a valve casing, a normally closed valve therein, a diaphragm casing having a control pressure connection, a diaphragm in said casing, an open post connecting said valve and diaphragm casings and having a bottom plate closing said valve casing, a stuffing box in said bottom plate, a valve stem traversing said stuffing box and post and operatively engaged with said diaphragm, a cross-head engaging said stem, levers pivoted on said post and engaging at their inner ends said cross-head, and adjust- 100 105 110 115 120 125 130

able springs carried by said post and engaging the outer ends of said levers to close said valve in opposition to said diaphragm.

9. In a device of the class described, and in combination, a valve casing, a normally closed valve therein, a diaphragm casing having a control pressure connection, a diaphragm in said casing, an open post connecting said valve and diaphragm casing having a bottom plate to close said valve casing and spring supporting extensions, a stuffing box disposed centrally of said bottom plate, a valve stem traversing said stuffing box and post and operatively engaged 15 with said diaphragm, a cross-head engaging said shouldered stem, levers pivoted on said post and engaging at their inner ends said cross-head, and adjustable springs carried by said bottom plate extensions and engaging 20 the outer ends of said levers to close said valve in opposition to said diaphragm.

10. In a device of the class described, and in combination, a valve casing, a valve there-

in, a diaphragm casing having a control pressure connection, a diaphragm in said casing, valve-opening levers mounted in said casing with their short ends coupled to said diaphragm, an open post connecting said valve and diaphragm casings, a stuffing box between said valve and diaphragm casings, 25 a valve stem traversing said stuffing box and post and engaging the long ends of said valve opening levers, valve closing levers pivoted on said post and engaging at their inner ends said stem, and adjustable springs 30 carried by said post and engaging the outer ends of said levers to close said valve in opposition to said diaphragm.

In testimony whereof I have hereunto set my hand in presence of two subscribing witnesses. 40

ROBERT H. MUELLER.
